UNITED STATES PATENT OFFICE.

A. F. JONES, OF DOUGLAS, MASSACHUSETTS.

IMPROVEMENT IN REGISTERS FOR ACCOUNT-BOOKS.

Specification forming part of Letters Patent No. 40,106, dated September 29, 1863.

To all whom it may concern:

Be it known that I, A. F. JONES, of Douglas, in the county of Worcester and State of Massachusetts, have invented a new and improved table for accountants, which I term the "Merchant's Monitor;" and I do hereby declare that the following is a correct description of the same, reference being had to the accompanying drawings, making part of this specification, and to the letters of reference marked thereon.

Figure 1 is a plan of the table and casing. Fig. 2 is a front elevation of the same with the case of books I' removed. Fig. 3 is a vertical section through the axis of the spindle by which the table revolves, and through the centers of two of the cases of books. Fig. 4 is an isometric view of one of the cases containing a tier of books.

With many manufacturers, with storekeepers, who have many accounts, and others it has become the practice to have accounts kept in small books, where each item is entered as the transaction occurs, thus each person's account is always posted, and each entry the only and the original one. This system avoids the labor and risk of error in transferring through day-book, journal, and ledger; but as each person's account is kept in a separate book, instead of all being kept in a ledger, it becomes desirable to arrange these small account-books so they can be readily found. The method most commonly adopted is to have a long case filled with a convenient number of tiers of books, each book having printed the name of the person whose account it contains, on its end, the partition under or over the book having a corresponding name upon it. The objections to this arrangement are, the liability of the clerks, where there are more than one, to interfere with each other when searching for books, the room it occupies, and the time consumed in removing the books from the case for safety when the place of business is closed.

To remedy these objections is the object of my present invention, which consists in having a revolving table with openings for six or more cases containing tiers of books. These cases, filled with books, can readily be removed from the table B to the safe, and vice versa. The circular form so condenses that

the table occupies but little room, and is more convenient for the clerks, as two or three may stand near it, and with facility find the book wanted, as they are numbered as well as alphabetically arranged.

To enable others skilled in the art to make and use my invention, I will proceed to describe its construction and operation by explaining the accompanying drawings.

A is the outer cases; B, the revolving table, having a spindle, C, which turns in a step, D, in the lower part of the case A, and having an upper bearing at E. The table is arranged for six cases, I, and one case, I', each containing a tier of eight books; but the number of cases of books may be increased or diminished, as also the number of books in a case. The spaces K between the book-cases are for figures, to which the numbers on the books correspond, and also for the names of persons, the account-book for any person being in the nearest partition to the number and name. The names in practice are made so that they can readily be removed and a new one substituted. The blocks representing account-books are numbered from one to forty-eight.

The merchant's monitor may be placed in an opening between the counting-room and the sales-room, so that persons in different rooms can have ready access, which could not be arranged with the long cases unless open through and the books and case lettered on both front and back. For those who have no fire-proof safe, I propose to make the outer casing with doors that will draw together and fasten, inclosing the whole table, thus locking up the account-books, and making the monitor portable.

Having thus described the construction and operation of my invention, what I claim, and desire to secure by Letters Patent, is—

The merchant's monitor, being circular, to economize room, revolving, for greater convenience and to save steps by bringing the books round to the operator, with movable cases, and alphabetically and numerically arranged, essentially as above described.

A. F. JONES.
